UNITED STATES PATENT OFFICE.

ERNEST V. FENTON, OF DES MOINES, IOWA.

LADDER.

1,142,806.

Specification of Letters Patent. Patented June 15, 1915.

Application filed December 26, 1913. Serial No. 808,663.

To all whom it may concern:

Be it known that I, ERNEST V. FENTON, a citizen of the United States, residing in Des Moines, county of Polk, and State of 5 Iowa, have invented a new and useful Improvement in Ladders, of which the following is a specification.

The object of my invention is to provide a ladder adapted for house painting, and the 10 like, which can be moved laterally, by the painter, without the necessity of his leaving his seat, or being greatly disturbed in his occupation.

My invention consists of certain details of 15 construction hereinafter set forth, pointed out in my claim, and illustrated in the accompanying drawings, in which—

Figure I shows a side elevation view of a ladder fitted out with my improvement. 20 Figs. II, III, IV, V and VI show detail views of their respective parts, and Fig. VII shows a modified form of a track and carriage which I occasionally employ.

Referring to the accompanying drawings, 25 the reference numeral 10 is used to indicate the lower section of a ladder mounted on a wheel carriage 11, as shown, the drive wheel 12 having rigidly secured to its inner face a grooved wheel, or drum, 13. The 30 wheels of the carriage are grooved, and travel on a track 14, or, as I show in the modified form illustrated in Fig. VI, the wheels may be of any construction desired and operate in a grooved track.

35 The ladder may be of any desired number of sections built up of mating sections held in place by any ordinary means such as shown at 15. At the upper extremity of the upper section I have placed a removable 40 frame 16, provided on its inner end with a wheel 17, the periphery of which is designed to engage the side of the house and travel thereon when the ladder is moved.

The numeral 18 indicates a seat, and the 45 numeral 19 a footboard, the two being secured to a frame 20, removably secured to the ladder at any point, by means of an

arm 21, provided with a hooked end designed to hook over any desired rung of the ladder, and a V shaped brace rod 22, designed as a support. 50

On the forward and outer end of the seat is secured an inwardly projecting brace 23, to which is mounted a wheel 24 designed to engage the side of the house and to travel 55 thereon when the ladder is moved.

Near the upper extremity of the upper section of the ladder, and within easy reaching distance of the operator is mounted a hand wheel 25, provided with a grooved 60 drum over which a cable 26 is designed to pass extending downwardly therefrom to engagement with the wheel 13.

It is obvious that an operator moving the hand wheel 25, at the top of the ladder, will 65 cause the said ladder to move in either direction desired, according to the direction in which he moves the hand wheel.

Having thus described my invention, what I claim and desire to secure by Letters Patent of the United States is:

A house ladder of the type described, including a ladder, mounted for movement in a direction parallel with respect to the house and equipped with a seat-forming structure 75 or frame arranged to be positioned laterally of the ladder, said ladder having its upper end provided with a bearing arranged for rotation in accordance with the indicated movement of the ladder, said seat-forming 80 structure or frame being provided with ladder-attaching members arranged to engage rounds of the ladder, whereby said seat structure is caused to face in the direction of the propping of the ladder, said seat structure also having an outstanding bearing member arranged to have a corresponding 85 rotating movement with the rotation of the bearing of the ladder.

ERNEST V. FENTON.
